UNITED STATES PATENT OFFICE.

CHARLES LIONEL MARCUS, OF NEW YORK, N. Y.

DESIGN FOR A LIP-STICK HOLDER.

Application filed September 11, 1924, Serial No. 10,736, and in France March 17, 1924. Term of patent 14 years.

To all whom it may concern:

Be it known that CHARLES LIONEL MARCUS, a citizen of the United States, and resident of the city of New York, in the county of New York and State of New York, has invented a new, original, and ornamental Design for Lip-Stick Holder, of which the following is a specification, reference being had to the accompanying drawing, forming part thereof, in which—

Fig. 1 is a top plan view of a lip stick holder embodying my new design; and

Fig. 2 is a vertical elevational view thereof.

An important feature of the design is the arrangement of parallel longitudinal bands or strips, alternating in width and color.

I claim:

The ornamental design for a lip stick holder as shown and described.

Dated New York city, September 9, 1924.

CHARLES LIONEL MARCUS.
